UNITED STATES PATENT OFFICE.

JOHN CONTOS, OF GRAND ISLAND, NEBRASKA.

TRACK-ADJUSTING DEVICE.

1,070,414.

Specification of Letters Patent. Patented Aug. 19, 1913.

Application filed October 2, 1912. Serial No. 723,592.

To all whom it may concern:

Be it known that I, JOHN CONTOS, a citizen of the United States, residing at Grand Island, in the county of Hall and State of Nebraska, have invented a new and useful 5 Track-Adjusting Device, of which the following is a specification.

The present invention relates to an improvement in track adjusting devices, this 10 particular structure being an improvement upon the structure shown in applicant's Patent No. 1,013,987, granted to him January 9, 1912, the primary object of the present invention being the provision of additional 15 mechanisms whereby the necessary operations for adjusting the tracks and ties may be carried out with a single apparatus.

With the foregoing and other objects in view which will appear as the description 20 proceeds, the invention resides in the combination and arrangement of parts and in the details of construction hereinafter described and claimed, it being understood that 25 changes in the precise embodiment of the invention herein disclosed can be made within the scope of what is claimed without departing from the spirit of the invention.

In the drawings—Figure 1 is a side elevation of the device when used for removing 30 or setting a tie. Fig. 2 is a perspective view of the tie engaging member. Fig. 3 is a perspective view of the wedge for actuating the tie engaging member.

Referring to the drawings, the numeral 1 35 designates a frame which has formed integral with the lower end thereof, the apertured lug 2, the capstan 3 being rotatably mounted in the frame 1 and carrying upon the lower end thereof, the actuating gear 4, the purpose of which will presently appear.

Where the device is used in connection 40 with removing and renewing the ties T, the frame 1 has its lug 2 connected to the V-shaped wedge 32 and such V-shaped wedge 45 32 is disposed between the actuating arms 33 of the toothed tongs 35, these tong members being relatively connected to each other by means of the connecting link 34. The

toothed members are disposed to straddle the tie T, while the bar 11 and its rack engaging portion 13 are placed against the rail 14, thus the rotation of the capstan 3 will move the frame 1 in the direction of the arrow Fig. 1, and will bear against the rail 14 and toward the wedge 32 to spread the arms 55 33 and thus securely hold the tongs in engagement with the tie, which will be moved in an opposite direction to the pressure against the rail 14 or with the frame 1.

What is claimed is:

1. In a track adjusting device, a bar provided with rail abutting terminals, one portion of the bar being toothed, a frame slidably mounted upon the bar, a capstan connected to the frame, a gear operated by the 60 capstan for engaging the toothed bar to move the frame relatively to the bar, a pair of tie engaging tongs having converging operating ends, and a wedge connected to and carried by the capstan and disposed between 65 the said converging ends of the tongs, whereby the movement of the frame upon the bar will close the tongs upon a tie when moved in opposition to the track engaging portion of the bar.

2. In a track adjusting device, a bar provided with rail abutting terminals, one portion of the bar being toothed, a frame slidably mounted upon the bar, a capstan connected to the frame, a gear operated by the 70 capstan and engaging the toothed bar to move the frame relatively to the bar, an expandable and toothed means for engaging a tie, and coöperable means carried thereby and the capstan for collapsing said means to 75 engage the tie when the frame is moved in one direction, the movement of the frame in the other direction releasing the tie engaging means.

In testimony that I claim the foregoing as 80 my own, I have hereto affixed my signature in the presence of two witnesses.

JOHN CONTOS.
